UNITED STATES PATENT OFFICE

169,429

SHOE RACK OR SIMILAR ARTICLE

Henry A. Enrich, New York, N. Y., assignor to Henry A. Enrich & Co. Inc., New York, N. Y., a corporation of New York

Application November 22, 1952, Serial No. 22,417

Term of patent 7 years

(Cl. D33—8)

To all whom it may concern:

Be it known that I, Henry A. Enrich, a citizen of the United States, residing at New York, in the county of New York and State of New York, have invented a new, original, and ornamental Design for a Shoe Rack or Similar Article, of which the following is a specification, reference being had to the accompanying drawing, forming part thereof.

In the drawing:

The single figure of the drawing is a perspective view of a shoe rack or similar article showing my new design.

I claim:

The ornamental design for a shoe rack or similar article, as shown.

HENRY A. ENRICH.
